RESHAPING DEVICE FOR TIES

Filed Feb. 14, 1931

INVENTOR
Pascual Perez
BY *Soltau & Blackley*
ATTORNEY

UNITED STATES PATENT OFFICE

PASCUAL PEREZ, OF NEW YORK, N. Y.

RESHAPING DEVICE FOR TIES

Application filed February 14, 1931. Serial No. 515,735.

This invention relates to new and useful improvements in reshaping devices for ties.

The invention has for an object the provision of a reshaping device for ties which is characterized by a pair of wire frames arranged in the same plane and adjacent each other with the adjacent sides curved away from each other and having their outer sides straight and diverging from their front ends to their rear ends, and means rigidly connecting a pair of adjacent points on said adjacent sides whereby said pair of wire frames may pivot resiliently to fit within ties having various sloping sides.

As another object of this invention it is proposed to form each of the frames of a single piece of wire bent in the shape of an elongated loop with a clip serving to hold the ends together.

The invention furthermore proposes the provision of curled portions upon the rear ends of the frames into which one may engage the fingers to conveniently handle the device.

A still further object of this invention is the provision of points upon the rear ends of the frames at the outer sides so as to be capable of engaging into the material of the necktie for maintaining a stretched condition of the tie.

The invention has for a still further object the arrangement of an adjustment for changing the position of the means which rigidly connects the adjacent sides of the wire frame so as to change the natural inclinations of the outer sides.

It is still further proposed to construct portions of the curved adjacent sides of the wire frame of rectangular cross section, to arrange a slideable joiner upon the sections, and a means for clamping the joiner in various adjusted positions to constitute the adjustments stated in the previous paragraph.

A still further object of this invention is the construction of a reshaping device for ties which is of simple durable construction, dependable in use and efficient in action, and which can be manufactured and sold at a reasonable cost.

For further comprehension of the inven-

tion, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is an elevational view of a reshaping device for ties constructed according to this invention.

Fig. 2 shows the device of Fig. 1 in the condition in which it is when engaged within a tie.

Fig. 3 is a horizontal sectional view taken on the line 3—3 of Fig. 1.

Fig. 4 is a horizontal sectional view taken on the line 4—4 of Fig. 1.

Fig. 5 is a sectional view of a portion of a tie and a portion of the reshaping device engaging the tie seen as though taken on the line 5—5 of Fig. 2.

Fig. 6 is a view similar to Fig. 1, but illustrating a modification of the invention.

Fig. 7 is an enlarged sectional view taken on the line 7—7 of Fig. 6.

The reshaping device for ties constructed according to this invention comprises a pair of wire frames 10 and 11 arranged in the same plane and having adjacent sides 12 curved away from each other. The outer sides 13 of the frames diverge from the front ends to the rear ends. Each of the frames must be formed from resilient material such as resilient wire or the like. From an inspection of Figs. 3 and 4 it will be seen that the frames are arranged in the same plane so that when engaged within a necktie will serve to stretch the tie into a flat condition.

Each of the frames 10 and 11 is constructed from a single piece of wire in the form of an elongated loop. This wire has a point 14 at one end, then extends straight for forming the inclined side 13 of the frame, then connects with a bent portion 15 connected with the curved side 12 which terminates in the vicinity of the point in a curled portion 16. The point 14 extends further down than the curl portion so as to be exposed on all sides. A clip 17 rigidly connects adjacent points

of the straight side 13 and the curled portion 16. This clip preferably should be soldered in place to form the rigidity called for.

A means is also provided for rigidly connecting the frames 10 and 11 at a pair of adjacent points along the said adjacent sides 12, whereby said pair of wire frames may pivot resiliently to fit within ties having various sloping sides. This means is in the form of a metallic clip 18 engaged around the points of the sides 12 and then firmly soldered into place so as to rigidly hold the wire frames in the same planes. In Fig. 1 the device is shown in a relaxed condition. In Fig. 2 the dot and dash lines 19 indicate a tie, and the device is shown under stress within the supposed tie.

In Fig. 2 it should be noticed that portions of the curved sides 12 have been flattened out resiliently when the device was placed within the tie so that it acts to tend to expand and thus urge the straight sides 13 against the sides of the tie. It should be noticed that the frames 10 and 11 may rock around the metallic clip 18 to positions wherein the inclined sides 13 correctly fit against the sloping sides of the tie. It is intended that the device be inserted within the hollow opening of the tie. The operator may place the forefinger through one of the loops 16 and the thumb through the other loop 16 and in this manner insert and remove the device from the tie as is required. To hold the device within the tie, the points 19 may be engaged against the material of the tie in a manner, as for example as shown in Fig. 5. This engagement serves to prevent the device from slipping out either fully or partially and thus losing some of its tension.

In Figs. 6 and 7 another form of the device has been illustrated, in which an adjustable means has been shown for rigidly connecting a pair of adjacent points on the adjacent sides of the frames, whereby said pair of wire frames may be adjusted to naturally maintain various positions with the outer sides sloping at angles to fit ties of different shapes. This means is in the form of a joiner member 20 formed with a rectangular opening 21 slidably engaging rectangular positions 22 of the adjacent curved sides 12. Set screws 23 threadedly engage through the joiner member 20 and abut against the flat portions 22 to maintain the position of the joiner. When the screws 23 are loosened, the member 20 may be slipped upwards or downwards to different places along the curved sides 12 and thereafter secured in the newly adjusted position by the screws 23.

The reshaping device for ties may be used generally to place a worn necktie back into new condition. The device may be used after the tie has been properly cleaned and upon use will serve to hold the tie in correct shape especially during drying when the tie was

dipped into a liquid to do the cleaning. After the tie has been properly stretched and held in the correct position for a sufficient length of time, as is determined by each individual case, the reshaping devise may be removed and the tie will maintain its correct form.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A reshaping device for ties, comprising a pair of wire frames in the same plane and having adjacent sides curved away from each other and outer sides straight and diverging from their front ends to their rear ends, and means rigidly connecting a pair of adjacent points on said adjacent sides whereby said pair of wire frames may pivot resiliently to fit within ties having various sloping sides.

2. A reshaping device for ties, comprising a pair of wire frames in the same plane and having adjacent sides curved away from each other and outer sides straight and diverging from their front ends to their rear ends, and means rigidly connecting a pair of adjacent points on said adjacent sides whereby said pair of wire frames may pivot resiliently to fit within ties having various sloping sides, each of said wire frames being formed from a single piece of wire bent into substantially loop shape.

3. A reshaping device for ties, comprising a pair of wire frames in the same plane and having adjacent sides curved away from each other and outer sides straight and diverging from their front ends to their rear ends, and means rigidly connecting a pair of adjacent points on said adjacent sides whereby said pair of wire frames may pivot resiliently to fit within ties having various sloping sides, each of said wire frames being formed from a single piece of wire bent into substantially loop shape, said wire starting with a pointed portion, then extending straight to constitute the straight outer side of the frame, then bent around for presenting the curved side, and finally bent into a curl at the rear end for engagement of one's finger in conveniently handling the frame.

4. A reshaping device for ties, comprising a pair of wire frames in the same plane and having adjacent sides curved away from each other and outer sides straight and diverging from their front ends to their rear ends, and means rigidly connecting a pair of adjacent points on said adjacent sides whereby said pair of wire frames may pivot resiliently to fit within ties having various sloping sides,

each of said wire frames being formed from a single piece of wire bent into substantially loop shape, said wire starting with a pointed portion, then extending straight to constitute the straight outer side of the frame, then bent around for presenting the curved side, and finally bent into a curl at the rear end for engagement of one's finger in conveniently handling the frame, and a clip engaging a portion of said curl and a portion of the straight side of the frame for rigidly connecting the frame into a resilient unit.

5. A reshaping device for ties, comprising a pair of wire frames in the same plane and having adjacent sides curved away from each other and outer sides straight and diverging from their front ends to their rear ends, and means rigidly connecting a pair of adjacent points on said adjacent sides whereby said 20 pair of wire frames may pivot resiliently to fit within ties having various sloping sides, each of said wire frames being formed from a single piece of wire bent into substantially loop shape, said wire starting with a pointed portion, then extending straight to constitute the straight outer side of the frame, then bent around for presenting the curved side, and finally bent into a curl at the rear end for engagement of one's finger in conveniently 30 handling the frame, and a clip engaging a portion of said curl and a portion of the straight side of the frame for rigidly connecting the frame into a resilient unit, the pointed ends of said wires extending past 35 said curls so as to be free and engageable against the material of a tie to hold the device within the tie.

6. A reshaping device for ties, comprising a pair of wire frames in the same plane and 40 having adjacent sides curved away from each other and outer sides straight and diverging from their front ends to their rear ends, and means rigidly connecting a pair of adjacent points on said adjacent sides whereby said 45 pair of wire frames may pivot resiliently to fit within ties having various sloping sides, comprising a clip engaged around points on said adjacent sides and soldered against motion onto the sides.

50 7. A reshaping device for ties, comprising a pair of wire frames in the same plane and having adjacent sides curved away from each other and outer sides straight and diverging from their front ends to their rear ends, and 55 means rigidly connecting a pair of adjacent points on said adjacent sides whereby said pair of wire frames may pivot resiliently to fit within ties having various sloping sides, said means being adjustable to various positions along the curved sides so as to change 60 the natural angles of said sloping sides.

8. A reshaping device for ties, comprising a pair of wire frames in the same plane and 65 having adjacent sides curved away from each other and outer sides straight and diverging

from their front ends to their rear ends, and means rigidly connecting a pair of adjacent points on said adjacent sides whereby said pair of wire frames may pivot resiliently to fit within ties having various sloping sides, 70 said means being adjustable to various positions along the curved sides so as to change the natural angles of said sloping sides, the adjustment being accomplished by means of a joiner member with a rectangular opening 75 slidably engaged upon square portions of said curved sides, and set screws threadedly engaged through the joiner member and abuttable against the curved sides for holding the joiner member in fixed positions.

In testimony whereof I have affixed my signature.

PASCUAL PEREZ.
